UNITED STATES PATENT OFFICE.

GEORGE H. AYLWORTH, OF BRIGHTON, ILLINOIS.

IMPROVEMENT IN STALK-HOLDERS.

Specification forming part of Letters Patent No. 127,212, dated May 28, 1872.

SPECIFICATION.

Be it known that I, GEORGE H. AYLWORTH, of Brighton, in the county of Macoupin and State of Illinois, have invented a new and useful tool or implement for quickly and easily grasping and firmly holding in a convenient bundle corn-stalks or other similar material, so that it may be easily and expeditiously handled or carried and loaded or unloaded, of which the following is a specification, reference being had to the accompanying drawing, which is a top view of the implement.

A A represent two handles, which are attached to or are a part of two or more arms, B B, which are hinged together at the base of the circle, so that the opening apart or closing together of the handles will give a corresponding opening and closing motion to the arms B B.

By closing the handles together, and con-

sequently the arms, after encircling a desired bundle of stalks, and fastening the two handles together by means of a ratchet-bar, C, or other similar device, the bundle of stalks is firmly held, so that it may be conveniently handled to be carried or loaded and unloaded.

By the use of this implement a tedious and burdensome operation to the farmer is made easy and rapid.

I claim as my invention—

The implement herein described for handling corn-stalks and analogous substances, consisting of the arms B, handles A, ratchet-bar C, and holding-pin, arranged as shown, substantially as specified.

GEORGE H. AYLWORTH.
